PYROPHORIC FLAME PRODUCING
MECHANISMLouis V. Aronson, Newark, N. J., assignor to Art
Metal Works, Inc., a corporation of New Jersey

Application July 6, 1935, Serial No. 38,963

5 Claims. (Cl. 67—4.1)

My invention relates to pyrophoric lighting mechanism comprising means operable by manual pressure applied to a torch to produce a freely burning flame at the end of said torch.

5 My invention has reference generally to improved features and arrangements relating to the construction and operation of pyrophoric lighters of the class comprising a torch utilizable as an operating member for producing the shower 10 of pyrophoric sparks.

Various other advantages, features and characteristics of my invention will become apparent from the following detailed description.

15 My invention resides in the flame-producing mechanism, features, arrangements and combinations of the character hereinafter described and claimed.

For an understanding of my invention and for an illustration of one of the many forms thereof, reference is to be had to the accompany drawing, in which:

Figure 1 is a plan view of my novel mechanism;

Fig. 2 is an elevational view, partly in section, showing various parts of my novel mechanism in 25 disassembled relation;

Fig. 3 is a fragmentary vertical sectional view, partly in elevation, showing my novel mechanism after operation thereof has been effected;

Fig. 4 is a vertical sectional view, partly in 30 elevation, showing my novel mechanism in normal condition;

Fig. 5 is a fragmentary vertical sectional view, partly in elevation, showing an arrangement of my novel mechanism; and

35 Fig. 6 is a fragmentary horizontal sectional view, partly in plan, and is taken on the line 6—6 of Fig. 2.

Referring to the drawing, the herein described mechanism is shown as comprising a top plate 1 which is suitably secured, as by a plurality of 40 screws 2 interiorly of the circular depending flange 3a of a cover plate 3. A pair of spaced frame members 4, 5 depend from the top plate 1, these frame members, preferably, being disposed in substantially parallel relation as shown in Fig. 4 and being soldered or otherwise suitably secured to the lower surface of said top plate 1.

As illustrated, the frame member 4 terminates 50 in a lower lateral section 4a which slidably receives the lower end of a reciprocatory actuating bar 6 extending vertically through aligned openings formed in the plates 1 and 3, said bar 6 terminating in an upper lateral section 6a to 55 which is secured a cup-shaped member 7. The

lower end of the bar 6 is reduced in width so as to form a flange 6b, Fig. 2, a helical spring 8 being disposed around said lower end of the bar 6 with the upper end thereof engaging the flange 6b and the lower end thereof engaging the lateral section 4a of the frame member 4. By virtue of this arrangement, the bar 6 is continuously biased in an upward direction.

As shown, a fixed supporting member 9 extends horizontally and is supported by the frame members 4 and 5, this member 9 pivotally supporting a pair of levers 10 and 11. In the form of the invention herein shown, the lever 10 is confined between two spacing members 12 and 13 disposed, in freely rotatable relation, on the supporting member 9. The lever 10 terminates in a slotted end 10a disposed in slidable engagement with respect to a pin 14 secured to and extending laterally from the aforesaid bar 6. The lower end of the lever 10 carries a lateral pin 15 to 20 which one end of a helical spring 16 is secured, the other end of said spring being secured to a pin 17 extending laterally from and secured to an extension of the aforesaid lever 11.

As indicated in Fig. 6, the lever 11 is secured in 25 suitable manner to the spacing sleeve 13 so as to be oscillatory therewith. This lever 11 comprises an upper arcuate section terminating in peripheral gear teeth 18, said arcuate section extending through aligned slots formed in the plates 30 1 and 3, the gear teeth 18 being utilizable as hereinafter described. As clearly shown in Figs. 2 and 3, the lever 11 comprises a nose 11a normally engaged by the aforesaid pin 15 which was described as projecting laterally from the lever 10. 35

In Fig. 2, the lever 11 is illustrated as in its normal position, said lever being releasably retained in said position by a suitable latch such, for example, as herein exemplified by the pawl 19 which is pivoted on a pin 20 extending laterally from an extension of the frame member 4. The pawl 19 is biased in a counter-clockwise direction, Fig. 2, by a spring 21 coiled around said pin 20 whereby said pawl is releasably latched in engagement with a pin 22 extending laterally from the lever 11. The pawl 19 comprises a lateral section 19a adapted to be actuated in the manner hereinafter described so as to swing said pawl 19 clockwise from the position shown in Fig. 2.

Extending vertically above the cover plate 3 are a pair of spaced standards 23, 23a which are secured to said cover plate in any suitable manner, as by soldering. If desired and as herein shown, the standard 23 may be an upper exten- 55

sion of the frame member 4. The standards 23, 23a form a support for a pyrophoric sparking unit of any suitable character.

Thus, for example, said unit may comprise a serrated wheel 24 of the usual type, this wheel being engaged by a pyrophoric member 25 which in part projects from a tube 26 extending downwardly through the plates 3, 1 and, preferably, being anchored to the frame member 4. The tube 26 contains the usual helical spring, not shown and the lower end of said tube is closed by a threaded plug 27 which holds the spring under compression whereby the pyrophoric member 25 is biased into engagement with the serrated wheel 24.

As illustrated in Fig. 5, the serrated wheel 24 defines an axial circular passage, the surface of which is formed with ratchet teeth 24a, said serrated wheel being loosely mounted on one end of a supporting member having a lateral bore receiving a spring-pressed slideable pawl 29. The other end of said member 28 has a pinion 30 peened or otherwise suitably secured thereto, the teeth of this pinion being in meshing relation with respect to the aforesaid gear teeth 18 of the lever 11. As disclosed, screws 31 and 31a are threaded into the respective opposite ends of the supporting member 28, these screws being loosely supported by the respective standards 23, 23a.

In the form of my invention herein shown, there is provided a fuel casing F having a lower surface 33 preferably felt-covered, this fuel casing serving as a base for the herein disclosed mechanism. Upstanding from the top wall 34 of this fuel casing and communicating therewith is a tubular member 35 which is maintained in vertical position in any suitable manner, as by means comprising a clamping nut 36 which engages the top surface of said wall 34. As herein illustrated in Fig. 4, the fuel casing F contains a mass of cotton absorbent material 37 or the like, fuel such, for example, as high test gasoline being introduced into the fuel casing through an opening in the top casing wall 34, such opening being normally closed by a threaded plug 38, Fig. 2.

In accordance with the invention, the top of the fuel casing F is provided with a flanged circular surface 34a adapted to receive, in readily detachable manner, the lower end of a circular main casing M which may be and preferably is a sleeve-like member formed from sheet metal.

To assemble the mechanism herein disclosed, the main casing M is seated upon the fuel casing F with the lower main casing surface disposed interiorly of and in engagement with the flanged surface 34a of the fuel casing. The plates 1 and 3 are apertured as indicated at 39, Fig. 4, to provide a passage through which the upper end of the tubular member 35 extends. Accordingly, by virtue of such passage, the plates 1 and 3 may be seated upon the main casing M with the upper end of the tubular member 35 extending through the aperture 39 and with the mechanism carried by and below the plates 1, 3 disposed interiorly of the main casing M.

As clearly indicated in Fig. 4, the part of the tubular member 35 normally disposed above the plate 3 is threaded for the reception of a sleeve nut 40 which, when seated as shown in said Fig. 4, engages the upper surface of the plate 3 to thereby positively maintain the various parts of the mechanism in assembled relation.

In accordance with a preferred form of the in-

vention, the upper part of the main casing M is externally threaded and the flange 3a of the plate 3 is interiorly threaded. Therefore, prior to the assembly of the parts with the fuel casing F, the main casing M may be threaded to the plate 3 whereupon the assembling operation may proceed as heretofore described. Although it is important, it shall be understood that my invention is not to be limited to the feature last described.

As stated above, the tubular member 35 communicates with the fuel casing F. This tubular member is open at its top and it forms a passage, therefore, through which the lower end of a torch member T may be passed so as to position the same interiorly of said fuel casing. The torch member may be of any suitable construction such, for example, as disclosed in my pending applications Serial No. 727,060, filed May 23, 1934, or Serial No. 747,855, filed October 11, 1934. As herein shown, the torch member T comprises a tubular sleeve 41 which receives a tubular wick 42 having a metallic rod 43 extending centrally therethrough. The torch T comprises an upper handle section 44 formed with a lower flanged section 45 adapted to rest upon the upper surface of the sleeve nut 40, Fig. 4. When the torch T is thus positioned, the lower end thereof—the part bearing the exposed wick section—is disposed interiorly of the fuel casing F, Fig. 4, so as to have fuel transferred to said wick section.

When the mechanism of my invention is to be operated, the torch T is withdrawn from the tubular member 35 and the lower end of the torch rod 43 placed in engagement with the cup-shaped member 7. Thereupon, the application of downward pressure to the torch T causes the actuating bar 6 to be moved downwardly from the position shown in Fig. 2 to that shown in Fig. 3. In so doing, the lever 10 is swung in a counter-clockwise direction from the position shown in Fig. 2 toward that shown in Fig. 3 with the result that the pin 15 recedes from the lever nose 11a to thereby place the spring 16 under a greater and greater degree of tension. As stated, this spring 16 is connected to both of the levers 10 and 11 but the tensioning of said spring does not cause movement of the lever 11 because, at this time, said lever 11 is locked by the pawl 19 in the position shown in Fig. 2.

During continued movement of the lever 10 in a counter-clockwise direction from the position shown in Fig. 2, the end 10b of said lever approaches and finally engages the section 19a of the pawl 19 and, eventually in response to the application of pressure to said pawl, the latter is swung clockwise from the position shown in Fig. 2 to that shown in Fig. 3 with the result that the lever 11 is released for movement under the influence of the tensioned spring 16.

When the lever 11 is released as just described, the tensioned spring 16 acts thereon to swing the same in a counter-clockwise direction and with a snap action from the position shown in Fig. 2 to that shown in Fig. 3. This movement of the lever 11 continues until the nose 11a thereof again comes into engagement with the pin 15.

When the above described counter-clockwise motion of the lever 11 occurs, the lower end of the torch T is in substantially the position shown in Fig. 3. As will be clearly understood, the lever 11, while moving as described above with a snapping action, causes the pinion 30 to rotate in a clockwise direction, Fig. 3. As a result, the serrated wheel 24 is rotated in the same direction 75

with a snap action to thereby produce a shower of pyrophoric sparks, these travelling in the direction indicated in Fig. 3 and, upon coming in engagement with the exposed lower end of the wick 42, igniting the fuel thereon to produce a freely burning flame.

In this manner, the fuel on the torch T is ignited to thereby produce a flame which may be utilized for any desired purpose. For example, 10 said torch may be utilized for the ignition of a gas burner, cigarettes, pipes, etc., and, in so doing, said torch may be passed from hand to hand, if desired. When the torch has served its intended purpose, it may be reinserted in the 15 tubular member 35 to cause the lower end thereof to come within the fuel casing F whereby an additional charge of fuel is taken up for subsequent use in the same manner as hereinbefore described. Preferably, although not necessarily, the flame at 20 the lower end of the torch T is extinguished before reinsertion in the tubular member 35. However, if not thus extinguished, it will be understood that passage of the torch into said tubular member serves to snuff the flame.

25 When the torch T is removed from the cup-shaped member 7, the various parts automatically return to their respective normal positions. More particularly, the spring 8, which previously had been compressed in response to downward movement of the actuating bar 6, becomes free to and does expand. In so doing, the actuating bar 6 is elevated to its normal position as shown in Fig. 2, the levers 10 and 11, substantially as a unit and with the pin 15 remaining in engagement with the lever nose 11a, returning to their respective normal positions as shown in Fig. 2 and, when finally returned to said position, the pawl 19 again moving to latching position with respect to the pin 22. In this manner, the various 30 parts are returned to their respective normal positions and placed in condition for subsequent operation, the latter occurring in the same manner as hereinbefore described in detail when the actuating bar 6 is depressed by the application of pressure thereto by the torch T. During return 35 of the parts to their normal respective positions, the pinion 30 rotates in a counter-clockwise direction, Fig. 3. At this time, however, the serrated wheel 24 remains stationary, by virtue of the described ratchet connection and further by reason of the pressure exerted on said serrated wheel 24 by the pyrophoric member 25 and its biasing spring.

In view of the foregoing description, it is believed 40 obvious that the mechanism of the invention herein disclosed presents certain advantages which are non-existent in connection with prior art arrangements of the same general character.

Thus, as clearly appears from a consideration 45 of Fig. 1, the various parts above the cover plate are disposed in a compact manner and are advantageously positioned with respect to each other so as to facilitate efficient operation. As will be noted, the tubular member 35, which forms 50 the normal receptacle for the torch T, is positioned at one side of the sparking unit and immediately adjacent the member 7 which is engaged and depressed by the torch T. This arrangement of parts is highly advantageous from 55 an operating viewpoint and is considered a distinct feature of novelty not heretofore previously known or used. More particularly, it is old to have the torch receptacle (member 35), the cup-shaped member 7, or equivalent, and the sparking 60 unit mounted in line with the unit last named

between the receptacle and member 7. The disclosed arrangement differs from this in obvious respects and is advantageous. It shall be understood that the disclosed relation of these parts is not to be limited to lighting mechanism of the 5 exact type disclosed herein.

In addition to the foregoing, the actuating bar 6 is of a form well adapted for large scale production. This actuating bar, as disclosed in the present application, is a distinct improvement on 10 equivalent arrangements of the prior art by reason of the efficient and non-efficient manufacturing operations that may be practiced in connection therewith.

Further, the disclosed arrangement presents 15 many advantageous features not found in the prior art devices. Thus, the actuating mechanism per se is of a simplified type compared with existing arrangements; the provision of the fuel inlet interiorly of the main casing is advanta- 20 geous; the attachment of the main casing to the cover plate is a desirable feature; the configuration of the casings is well chosen from the view-point of space requirements, etc., etc.

While the invention has been described with 25 respect to a certain particular preferred example which gives satisfactory results, it will be understood by those skilled in the art after understanding the invention, that various changes and modifications may be made without departing 30 from the spirit and scope of the invention and it is intended therefore in the appended claims to cover all such changes and modifications.

What is claimed as new and desired to be secured by Letters Patent is:

1. In pyrophoric lighting mechanism, a spark- 35 ing unit, and a movable torch-actuated member disposed in the path of sparks projected from said unit, said member being a straight bar having a laterally disposed torch-engaging section at the top thereof, said bar, throughout the length thereof, being rectangular and of substantially greater width than thickness, said bar comprising a plurality of sections each of different width.

2. In combination, a casing, a sparking unit carried thereby, a movable member associated with said casing, said movable member having an actuating section disposed in the path of sparks projected from said sparking unit, a torch operable to move the actuating section of said movable member in said path, a spring in which energy is stored in response to such movement of said movable member, a lever controlled by said movable member, a lever controlling said sparking unit, a spring having its respective opposite ends connected to said levers, and latch means for delaying operation of said second lever.

3. In combination, a casing, a sparking unit carried thereby, a movable member associated with said casing, said movable member having an actuating section disposed in the path of sparks projected from said sparking unit, a torch operable to move the actuating section of said movable member in said path, a spring in which energy is stored in response to such movement of said movable member, a lever controlled by said movable member, a lever controlling said sparking unit, a spring having its respective opposite ends connected to said levers, and latch means for delaying operation of said second lever, such movement of said movable member storing energy in said second spring and release of said latch permitting transfer of said energy to said second lever and thence to said sparking unit.

4. In combination, a casing, a sparking unit carried thereby, a movable member associated with said casing, said movable member having an actuating section disposed in the path of sparks projected from said sparking unit, a torch operable to move the actuating section of said movable member in said path, a lever operatively connected with said actuating section and pivoted at a point within said casing beneath said sparking unit, a second lever operatively connected to said unit for actuating the latter, a spring interconnecting said levers and in which energy is stored in response to movement of said movable member, latch means for delaying operation of said second lever, said latch means coacting directly with said second lever, and means for releasing said latch means to thereby effect the transfer of energy to said second lever and thence to said sparking unit.
5. In combination, a casing, a sparking unit

carried thereby, a movable member associated with said casing, said movable member having an actuating section disposed in the path of sparks projected from said sparking unit, a torch operable to move the actuating section of said movable member in said path, a lever operatively connected with said actuating section and pivoted at a point within said casing beneath said sparking unit, a second lever operatively connected to said unit for actuating the latter, said second lever being pivoted adjacent said point, a spring interconnecting said levers and in which energy is stored in response to movement of said movable member, latch means for delaying operation of said second lever, and means on said first mentioned lever for releasing said latch, thus permitting transfer of said energy to said second lever and thence to said sparking unit.

LOUIS V. ARONSON. 20
